UNITED STATES PATENT OFFICE.

ROBERT GRIFFIN, OF NEW YORK, N. Y., ASSIGNOR TO THE ROBERT GRIFFIN CO., OF NEW YORK, N. Y., A CORPORATION OF NEW YORK.

DESIGN FOR CRETONNE, SILK, TAPESTRY, WALL-PAPER, OR PRINT GOODS.

50,472.

Specification for Design.

Patented Mar. 20, 1917.

Application filed November 4, 1916. Serial No. 129,618. Term of patent 7 years.

To all whom it may concern:

Be it known that I, ROBERT GRIFFIN, a citizen of the United States, residing at New York city, in the county of New York and State of New York, have invented a new, original, and ornamental Design for Cretonnes, Silks, Tapestries, Wall-Papers, or Print Goods, of which the following is a specification, reference being made to the accompanying drawing, forming part thereof.

The figure is a plan view of a piece of cretonne showing my new design.

I claim:

The original design for "cretonne, silk, tapestry, wall paper or print goods" as shown in the drawing.

ROBERT GRIFFIN.

Witnesses:

H. A. COOPER,
Jos. W. KRAUS.
